Patented Apr. 25, 1922.

UNITED STATES PATENT OFFICE.

WILLIAM B. NUTTING, OF GERVAIS, OREGON.

MEASURING DEVICE.

1,413,767.

Specification of Letters Patent. Patented Apr. 25, 1922.

Application filed September 9, 1921. Serial No. 499,400.

To all whom it may concern:

Be it known that I, WILLIAM B. NUTTING, a citizen of the United States of America, residing at Gervais, in the county of Marion 5 and State of Oregon, have invented certain new and useful Improvements in Measuring Devices, of which the following is a specification.

My present invention relates generally to 10 a combined measure and funnel for use in supplying oil in measured quantities to automobiles, for instance within the crank case and my object is the provision of a measuring device of funnel shape having an upper 15 measuring compartment with a valve at the base of the compartment of a nature which when open provides for a quick flow of oil downwardly through the spout, this valve being of such a nature that it may be readily 20 reached for repair and substitution of parts in case this becomes necessary by simply detaching the lower from the upper part of the device.

In the accompanying drawing which illustrates my present invention and forms a 25 part of this specification,

Figure 1 is a vertical sectional view through the device constituting my invention,

Figure 2 is a detail side view of the lower 30 part detached from the upper part,

Figure 3 is a top plan view, and

Figure 4 is a detail perspective view of the valve and its connections.

Referring now to these figures my invention proposes a measuring device of funnel shape in which the lower portion or spout 10 is detachably connected to the lower smaller end of the upper part 11 the latter of which 35 forms a measuring chamber and may have internal graduations 12. The upper part or body of the device is also provided with an upper curved bail or handle 13 and its top is partially closed by a plate 14 having an

40 opening in line with the axis of the body to receive the upper end of a valve controlling connection 15, for instance a wire whose upper end above the plate 14 has a ring 15^a immediately below the handle 13.

45 To provide for the detachable connection of the spout 10 to the body 11 the latter is internally threaded at its lower smaller end to receive a reduced threaded nipple 16 of the spout 11 and the upper edge of which 50 nipple in the connected position forms an

annular valve seat within the lower end of the body 11 on which a flat valve 17 sits with its washer 18. This valve is connected to the upper end of a stem 19 and is provided with diametrically opposed and upstanding ears 60 20 receiving through their apertures the lower outturned ends of an inverted U-shaped lift 21 centrally of which the lower end of the valve manipulating wire 15 is connected.

65 The nipple 16 has depending arms 22 supporting a lower apertured stem guide 23 through which the stem 19 passes, the upper end of this stem 19 being threaded as shown at 24 and screwing into and through the 70 valve 17 while its lower end has a head 25, preferably slotted crosswise as at 26 to receive a screw driver. Against this head rests the lower end of a spring 27 coiled around the lower portion of the stem 19 with 75 its upper end bearing against the stem guide 23 and as this stem projects downwardly into the spout 10 it is under normal circumstances merely necessary to insert a screw driver within the spout to engage the head 80 25 of the stem 19 and rotate the latter in order to adjust the tension of the spring.

In order to reach the valve it is simply necessary to unscrew the spout and it is quite obvious from the foregoing that the 85 construction I propose not only brings about these advantages with respect to ready accessibility of the parts, but also provides for easily cleaning the entire device.

The fact that the valve 17 is flat and seats 90 on the upper edge of the nipple 16 provides for a large passageway for the free outflow of oil both light and heavy when the valve is lifted and permits the flow to be readily controlled as well as providing for a uniform 95 even seating of the valve under normal circumstances under the tension of its spring so as to avoid leakage.

I claim:

1. A funnel shaped measuring device in 100 two parts of which the upper part is internally threaded at its lower smaller end, a handle on the upper part, an externally threaded nipple at the upper larger end of the lower part engaging the threads of the 105 upper part, and the upper end of which nipple forms a valve seat within the upper part, a valve on said seat having a stem projecting through the nipple and adjustable with respect to the valve, said stem having a lower 110

head, a spring around the stem between its said head and a portion of the nipple to normally hold the valve on its seat, and a valve manipulating connection extending vertically in the upper part to a point adjacent to the said handle thereof.

2. A funnel shaped measuring device having an upper handle and an internal member intermediate the ends thereof forming an annular valve seat, a flat valve seated downwardly on said seat, a stem depending through the seat forming member and having its upper end threaded in connection

with the valve and having at its lower end a slotted head accessible through the lower end of the funnel, a spring coiled around the stem between the said head and a portion of the said seat forming member, a valve manipulating connection leading upwardly from the valve, and a guide adjacent to the said handle for the said valve manipulating connection.

In testimony whereof I have affixed my signature.

WILLIAM B. NUTTING.
